UNITED STATES PATENT OFFICE

2,547,117

OVEN DOOR

Christopher L. Hardwick, Cleveland, Tenn.

Application January 15, 1947, Serial No. 722,206

1 Claim. (Cl. 20—56.5)

1

This invention relates to stove doors and more particularly to that type of oven door which is provided with a covered opening or window herein, thus enabling the housewife to note the progress of the baking or roasting at any time desired without opening the door itself.

Heretofore it has been the custom to cover the window opening in such doors with at least two spaced panes, the air space between them serving to reduce the escape of heat to a minimum. However, considerable trouble has been experienced due to the fact that the glasses could not be sealed tightly together and consequently, fumes and greasy odors from cooking would collect in the inaccessible space between them and from where they could not be readily cleaned off by the housewife.

One of the principal objects of the present invention is to overcome the foregoing objections by providing adequate seals at both outer and inner faces of the panes.

Another object of the invention is to incorporate the glazed unit in a sub-assembly which can be manufactured independently of the door itself and thereafer installed in the door as a unit.

Other objects and advantages of my invention will be apparent as the description is considered with the accompanying drawings in which:

Figure 1 is a perspective view of a stove showing my invention installed in the oven door thereof;

Figure 2 is a side elevation showing the door removed from the stove;

Figure 3 is a rear view of the door removed from the stove;

Figure 4 is a front face view of the lining plate and its brace member or plate disassembled from the front plate and showing the manner in which the window glass is attached in place;

Figure 5 is a section on line 5—5 of Figure 4; and

Figure 6 is a section on line 6—6 of Figure 4.

Referring more particularly to the drawings 1 denotes a cooking stove or range comprising a body 2 supported upon a base 3 and provided with top burner openings 4. The body 2 is also provided with side utility compartments 5, a single bottom utility compartment 6 and an oven compartment 7, all of conventional construction. The oven opening is normally closed by a door 8 hinged at its bottom edge in any desirable manner, not shown.

The oven door 8 consists of a front enameled rectangular sheet metal plate 9 and a back lining member or plate 10 also of sheet metal. The

2

front plate 9 is formed with flange 11, projecting inwardly or rearwardly from its side, top and bottom edges and adapted to receive or fit snugly over corresponding flange 12, projecting outwardly or forwardly from the side, top and bottom edges of the lining plate 10. The bottom horizontally disposed portion of inwardly or rearwardly extending flange 11 is formed with an upwardly bent extension 13 which prevents separation of the plates 9 and 10 at their lower ends. The upper end of the lining plate 10 seats against a pair of spacing brackets 14, only one of which is shown, secured to and projecting rearwardly from the upper rear face of the front plate 9. These brackets are provided with apertures 15, which register with corresponding apertures 16 in the lining plate for a purpose presently described. By first inserting the lower end of the lining plate behind the extension 13 the lining plate member 10 can be readily moved into place within the confines of flange 11, and in position to be secured to the front plate 10. This is accomplished by means of headed screws 50, adapted to be inserted forwardly through apertures 16 and thence through apertures 15, in the order named. Any suitable means, not shown, is employed to hinge the lower end edge of the oven door 8 to the stove body 2, and curved arms 20 projecting rearwardly and downwardly from the sides of flange 12, are formed with hooked shaped ends 21 adapted to be connected to conventional spring mechanism, not shown, for normally maintaining the door 8 in closed or open position. Both front plate 9 and lining plate 10 are provided with rectangular window openings 17 and 18 respectively.

Secured snugly to the lining plate in any suitable manner, as by welding contacting areas, is a brace member or plate 19, conforming in general outline and shape with plate 10, and serving to brace and reinforce the lining member or plate 10. This brace member is formed with a rectangular window opening 22 which, generally speaking, registers with the window openings 17 and 18 of plates 9 and 10, just described, and the intermediate portion of the brace member is bellied forwardly, as at 35, from the correspondingly rearwardly bent or bellied adjacent portion 36, of the lining plate 10, for a purpose presently described.

The window openings 17, 18 and 22, previously described, are normally closed by a readily assembled and disassembled window unit 23. This unit comprises a rectangular sheet metal frame member 24 in which front and rear glass mem-

bers 25 and 26 are supported, a rectangular spacing member 27, U-shaped in cross section and of thin slightly resilient sheet metal, being employed to hold the glass members apart. The body portion 28 of the sheet metal frame member 24, along the side, top and bottom portions thereof, is bent forwardly at right angles to the body portion 28 to provide a continuous forwardly extending flange 29. This flange 29 terminates at its forward edge in an inwardly bent narrow flange 30 against which the front edge face of the front glass 25 is tightly forced by the action of spacing member 27.

The body portion 28 of the frame member 24 is cut away or slit at intervals, as at 31, to provide a plurality of strips or tongues 33. The greater portion of these strips or tongues are then severed from the body portion 28, at points adjacent the rear edge of flange 29, and the remaining portions when bent inwardly, form seats against which the rear face of the rear glass 26 tightly seats. It will also be seen that the outwardly extending flanges 34, of the spacing member 27, are snugly received between the inner side edges of the opposing faces of the panes 25 and 26 and also that the outer free edges of these flanges 34 seat against the inner face of the forwardly bent flange 29. Furthermore it will be noted that the rear face of the body portion 28 of the frame member 24 seats snugly against and for attachment to the bellied portion 35 of brace plate 19. The parts just mentioned are secured together and to the brace plate 19, by screws 37, which pass through aligned openings in the parts 28 and 35, thus securing these parts of the glazed unit 24 together, and to the lining member or plate 10. When the parts are thus assembled the flanges 34 of U-shaped spacing member 27 crowd the glass into close contact with the flange 30 and tabs 33 while a tight contact will also be effected between the glass holding frame and the brace member 19. This prevents fumes or greasy products from gaining access to the dead air space between the panes.

The unit 24 can readily be assembled at the factory or at a point remote therefrom, and subsequently incorporated in the stove as a separate unit. At the same time this construction permits of ready disassembly for replacing glass when broken without interfering with the desired seal when re-assembled. The oven compartment 1 is preferably provided with an electric bulb, not shown, for illuminating the interior of this compartment.

Any suitable number of tabs 33 may be employed but preferably four (4) equally spaced tabs are used. This construction provides an economical means for securing one of the glass sheets in place and at the same time permits of the glass supporting frame being made from a single piece of sheet metal. In case of glass breakage it also affords an easy means of disassembly.

Having thus described my invention, what I claim is:

A window structure of the type described including a substantially rectangular sheet metal frame for supporting spaced glass sheets, in front of a conventional window opening, said frame member having a body portion cut away or slit at intervals to form a plurality of strips, a flange on said body portion extending forwardly at substantially a right angle to said body portion, a plurality of spaced glass sheets having their marginal edges in close contact with said flange, a U-shaped spacer member in close contact with said flange and the opposing inner side edges of said spaced glass sheets, the outer forward marginal edge of said flange being bent inwardly against the outer side edge of one of said glass sheets, inwardly bent tabs formed on said body portion at the base of said strips in close contact with another of said glass sheets, said strips and tabs being formed in pairs and one strip and tab being formed approximately midway the centers of the sides of the rectangular frame member and means on said body portion for detachably connecting the body portion of said glass sheets in front of the opening in said window and in position to close the said window opening.

CHRISTOPHER L. HARDWICK.
